UNITED STATES PATENT OFFICE.

BENJAMIN M. WALPOLE, OF PROVIDENCE, RHODE ISLAND, ASSIGNOR TO NATIONAL GAS FURNACE COMPANY, OF PROVIDENCE, RHODE ISLAND, A CORPORATION OF RHODE ISLAND.

HARDENING AND ANNEALING FURNACE.

1,412,152.

Specification of Letters Patent. Patented Apr. 11, 1922.

Application filed April 15, 1919. Serial No. 290,112.

To all whom it may concern:

Be it known that I, BENJAMIN M. WALPOLE, a citizen of the United States, and resident of the city of Providence, in the 5 county of Providence and State of Rhode Island, have invented certain new and useful Improvements in Hardening and Annealing Furnaces, of which the following is a specification.

10 This invention relates to furnaces adapted more particularly for annealing and hardening metal parts, and has for one of its objects to provide a furnace in which the heat zone is sealed against the entrance of outside 15 air while the work is being acted upon therein to prevent oxidization of the material.

A further object of the invention is to provide a combustion chamber about the 20 heat zone and separated from the zone to prevent direct contact of the blaze with the work when gas is used as a fuel thereby obtaining a more uniform heating effect upon the work and also preventing oxidizing 25 of the same while being treated.

A further object of the invention is to provide a rotatable carrier in which a plurality of spaced-apart work supporting members are mounted, said members being 30 independent of each other.

With these and other objects in view, the invention consists of certain novel features of construction, as will be more fully described, and particularly pointed out in the 35 appended claims.

In the accompanying drawings:

Figure 1 is a sectional side elevation showing the general arrangement of my improved furnace.

40 Figure 2 is a central sectional end elevation of the same.

Figure 3 is a sectional view showing a portion of a carrier having means whereby the work is automatically ejected from the 45 holder after it has been acted upon in the heat zone.

Referring to the drawings, 10 designates the oven portion which may be formed of brick or other suitable heat-resisting material, and within which is formed a combustion chamber 11, which chamber is provided with gas or fuel supply pipes 9 and a vent opening 12.

A partition 13 is formed in said chamber

to separate it from the inner space 14, which 55 I term the "heated zone". This oven and its partition are mounted on a table 34 and supported on suitable legs 15.

A carrier member 16 is rotatably mounted on the shaft 17 which is supported on bearings 18 from the table and this wheel is adapted to be rotated through the worm wheel 19, worm 20, shaft 21, and hand wheel 22 as desired.

This carrier is constructed essentially in 65 the form of a pair of spaced-apart wheels each having a plurality of oppositely disposed arms 23 radiating outwardly from the hub members 26, and between which arms the work supports 24 are pivotally mounted, 70 each on its pivoting rod 25, which work supports may be made in the form of baskets or receptacles as illustrated in Figures 1 and 2, or in the form of sockets 29 as illustrated in Figure 3, or in any other desired 75 form.

In arranging these work supports about the wheel, I preferably form them in groups and separate each group from the next adjacent group, and between these different 80 groups I provide a baffle plate 27 mounted on the wheel hubs and which plates are arranged to enter the heat zone and close both ends thereof to prevent circulation from the outer chamber or gas zone 30, presently described, during the work heating period and so more effectually confine the heat within this heat zone while the work is being treated.

A liquid bath tank 28 is provided through 85 which the work supports and the work are passed to cool the same, after the latter has been subjected to the high temperature in the heated zone.

One of the features of this invention is 90 that a thin wall or plate 33 is arranged to project downwardly from the table 34 and form a skirt about the work supports, the same extending into the tank below the water line, for the purpose of sealing this outer 95 chamber against the outside atmosphere.

In some cases it is also found desirable to fill this outer chamber with suitable non-oxidizing gases through the pipe 40 to more 100 effectually exclude the oxygen of the air and so effectually prevent oxidization of the work while being treated in the heat zone.

The articles of work are passed by the

hand of the operator down and deposited into the receptacles and after having been annealed they are removed from the baskets by hand at the other side of the machine.

5 By my improved construction of furnace the carrier proper is not subjected to action of the high temperature as it is effectively protected by the skirt 33 and double bands 31 and 32 of suitable heat-resisting material 10 which are disposed about the hubs 26.

By my improved construction each of the work supports is entirely independent of the other supports in this carrier, in that if one is displaced or out of order, it in no way 15 affects the operation of the others; then again the work support itself is extremely simple in construction and is readily removed from the carrier and replaced by another.

20 The heated zone may be elongated to receive work of any length.

In some instances it is desired to provide means for automatically discharging the work from the holders, and in Figure 3 I have 25 illustrated one means of accomplishing this result which comprises a wheel 35 on which are mounted a plurality of spokes 36 on which spokes are pivotally mounted at 37 the holders 29 into which the work 38 such 30 as drills or short rods, may be placed whereby when the work holders pass the vertical line in the heat zone they will automatically tip and swing downwardly into position to discharge the work therefrom.

35 This automatic operation, as illustrated, is but one of a number of ways in which this or a similar result may be accomplished.

In the operation of my improved annealing and hardening apparatus the work is 40 placed by hand into a pair of receptacles 24 then the device is rotated by means of the hand wheel 22 to bring this pair of hollow receptacles up into the heat zone. After the work has become thoroughly heated in this 45 zone the hand wheel 22 is again operated to bring the work from the heat zone down into the liquid on the other side from whence it is removed by the hand of the operator.

The foregoing description is directed 50 solely towards the construction illustrated, but I desire it to be understood that I reserve the privilege of resorting to all the mechanical changes to which the device is susceptible, the invention being defined and

limited only by the terms of the appended 55 claims.

I claim:

1. An annealing and hardening furnace comprising a rotary work carrier, a liquid tank, a heat zone above said tank and a skirt 60 extending downwardly into the tank liquid sealing said heat zone against the admission of outer air.

2. An annealing and hardening furnace comprising a revolving carrier, work supports mounted on said carrier, a heated zone into which the work supports are moved by the rotation of said carrier, a liquid tank into which the work is immersed and a set of baffle plates mounted on the carrier for closing the heat zone after the work has been admitted thereto.

3. An annealing and hardening furnace comprising a revolving carrier, a plurality of spaced apart work supports arranged 75 around and mounted on said carrier, all mounted to rotate about a common center, a combustion chamber, a heat zone into which the work is carried by said carrier, a cooling liquid into which the work is immersed, a 80 partition between said chamber and zone excluding the atmosphere from said zone while the work is being acted upon therein.

4. An annealing and hardening furnace comprising a revolving carrier, a plurality 85 of work supports pivotally mounted in spaced relation in said carrier to swing independently of each other, a heat zone, and means whereby said carrier may be rotated to advance said supports and the work into 90 said zone and then moved out of said zone after having been raised to a predetermined temperature.

5. An annealing and hardening furnace comprising a heat zone, a work carrier for 95 advancing the work into said zone, and a holder for the work on said carrier adapted to be positioned by gravity to discharge the work therefrom at a predetermined point in the travel of said carrier.

6. An annealing and hardening furnace comprising a heat zone, a set of movable work supports for carrying the work into said zone, said supports being mounted to be positioned by gravity to eject the work 105 after it has been acted upon in the heat zone.

In testimony whereof I affix my signature.
BENJAMIN M. WALPOLE.
